AMUSEMENT DEVICE.

Application filed December 22, 1927. Serial No. 241,852.

This invention relates to amusement devices and more particularly to coin controlled mechanisms involving a target toward which balls may be fired, and has for its object to provide a construction less costly to manufacture and more efficient to use than those heretofore proposed.

With these and other objects in view the invention consists in the novel details of construction and combinations of parts as will be more fully hereinafter disclosed and particularly pointed out in the claims.

Referring to the accompanying drawings forming a part of this specification in which like numerals designate like parts in all the views;—

Fig. 1 is a perspective view of an amusement device with parts broken away, to which this invention has been applied;

Fig. 2 is a vertical sectional view taken centrally of the device shown in Fig. 1 and more particularly illustrating the invention;

Fig. 3 is a detail sectional view illustrating the loading apparatus employed in this device;

Fig. 4 is a horizontal sectional view taken as on the line 4—4 of Fig. 3 and looking in the direction of the arrows;

Fig. 5 is a horizontal sectional view taken as on the line 5—5 of Fig. 2 and looking in the direction of the arrows;

Fig. 6 is a perspective view adapted to more clearly illustrate the target registering device and the means for resetting the same;

Fig. 7 is an enlarged detail view of some of the parts shown in Fig. 6;

Fig. 8 is a vertical sectional view taken as on the line 8—8 of Fig. 2 and looking in the direction of the arrows;

Fig. 9 is a vertical sectional view taken as on the line 9—9 of Fig. 2 and looking in the direction of the arrows; and

Fig. 10 is a horizontal sectional view taken as on the line 10—10 of Fig. 9 and looking in the direction of the arrows.

In order that this invention may be the better understood it is said that on September 1, 1925 there was granted to Walter A. Tratsch the United States Patent #1,551,858 entitled "Amusement device" in which there is disclosed a miniature shooting gallery provided with a target generally indicated by the numeral 3, and a pistol

generally indicated by the numeral 10 forming the subject matter of said patent.

The pistol disclosed in said patent is provided with a coin receiving slot, and an operating slide adapted to force a coin of requisite size past a locking lever whereby the actuating parts of the pistol will be placed in operative position so that balls can be successively fired from the pistol toward said target. The pistol is universally mounted by the provision of suitable pivots providing vertical and horizontal movement of the muzzle to cover the range of said target.

With particular reference to Figs. 3 and 7 of said patent and the specification thereof, it will be observed that the actuating slide 70 of said pistol is provided with a pin 81 rigid therewith, connected to one end of a lever 82 adapted to actuate, on the full stroke thereof, the counting mechanism generally indicated by the numeral 83.

Further, with special reference to Figs. 3 and 4 and the specification of said patent, it will be observed that there is provided a loading lever 137, pivoted as at 138, and controlled by a spring 141 which is adapted to be oscillated each time the trigger 131 is pulled through the medium of the pin 135, carried by the trigger member, working in the slot 136 of said lever 137.

The oscillations of said lever will cause one end of the same, constituting the lifting head 145, to reciprocate in the receiving tube 151 for loading the barrel with balls to be fired. Fig. 3 of said patent shows the lifting head 145 of the loading lever in elevated position, having just delivered a ball A into the barrel of the pistol, but in Fig. 4 it is clearly shown that said head 145 travels to such a lower position that a part thereof extends out of and below the casing of the pistol when the trigger is pulled. There is considerable force generated in the actuation of the loading lever and this force is utilized in the present invention.

In the amusement device now to be disclosed there is provided a pistol 10 substantially a duplicate in all its parts of the pistol disclosed in said patent but not universally mounted. On the other hand, it is mounted on vertical pivots, not shown, contained in a casing 1 adapted to form the front plate of, and be secured to, the cabinet

2 which houses this device, so that the muzzle of the pistol can be given a horizontal translation at the necessary elevated position to fire balls over the substantially horizontal 5 target plate 3 disposed within the cabinet under the usual plate glass cover for devices of this character. The target plate 3 is constructed to simulate a billiard table in that it is provided with a plane surface inclined 10 slightly to insure balls rolling thereover to a suitable opening 4 for return to the pistol. The lateral edge portions of the plate 3 are provided with rubber cushions 5 and openings, generally indicated by the numeral 6, 15 in the nature of pockets. In other words, at each of the four corners, and substantially midway of each long side of the plate there is provided an opening between adjacent rubber cushions so that balls fired from the 20 pistol may pass therethrough and drop into troughs or conduits, generally indicated by the numeral 7, each opening associated with a separate conduit which is so pitched as to cause a ball therein to roll away from said 25 opening.

As will be clear from Figs. 1 and 5 the conduits 7 converge, so that a ball in any conduit will roll into a trough like chamber 8 common to all of said conduits and whose 30 bottom is slightly inclined downwardly toward the converging narrow outlet end of said chamber. Communicating with said outlet is a special conduit or trap 9 the width of which is just slightly in excess of the 35 diameter of one of the balls fired by the pistol. The bottom of this trap 9 is pitched lower than the bottoms of the previously mentioned passageways for the balls so that said balls will positively enter said trap. 40 From the trap each ball may enter an elevator tube 15 and be raised to a platform 16 adapted to permit the balls to roll to and through an opening 17 therein and drop onto a pistol supported shelf 18 which is in turn 45 adapted to direct the balls therefrom into the receiving tube 151 of said pistol. The balls entering the receiving tube are then raised into the pistol barrel by means of the loading lever 137 in a manner fully disclosed 50 in said patent.

The operation of parts for returning the balls to the pistol will now be described. The shelf 18, as well as the platform 16, is made of sufficient size to accommodate several balls and the pistol with its operating mechanism is so constructed that when the last ball has been fired from the pistol for the inserted coin, the release of pressure on the trigger will automatically cause the 55 barrel to be reloaded with a ball, all as was disclosed in said patent. After the next coin has been inserted and the operating slide moved to unlock the pistol mechanism, said ball may be fired from the gun by pulling 60 the trigger, at which time the loading lever 65

137, due to its inter-connection with the trigger, will be oscillated in such manner that the lifting head 145 thereof will be forced downwardly. This action causes a hammer-like extension 20 of the head 145 to strike 70 the end of a lever 21, pivoted as at 22 to said pistol, and move the same downwardly into the dotted line position 23, see Fig. 2. The lever 21 as best illustrated in Fig. 5 is T-shaped, the part struck by the loading lever 75 137 forming the tail thereof and the part on the other side of the pivot 22 constituting the head 24 thereof which is curved as shown. The arc of said head is circularly formed about the axis of the vertical pinions 80 of the pistol as a center so that said head will always be able to cooperate with a stationary lever carried by the cabinet. The extent of the head 24 to both sides of the line of the tail is made in accordance with 85 the total horizontal translation of the pistol.

Thus it will be seen that, regardless of the position of the pistol at the time the trigger is pulled, the loading lever 137 will actuate the lever 21 and cause the same to operate 90

the short end of a stationary lever 25 pivoted as at 26 to a suitable supporting bracket 27 secured to the under side of the plate 3. The other end of the lever 25 is provided with a slot adapted to receive a pin 28 95 mounted in a piston or elevator 29 slidably disposed in the elevator tube 15 so that, upon the oscillation of said lever 25, the piston 29 will be depressed against the tension of a spring 30 disposed therebelow in said tube. The parts are so dimensioned that when the piston 29 is in its lowermost position, as seen in Fig. 2, it will uncover an opening 31 in the wall of the tube 15 communicating with the interior of the trap 9, said opening 100 adapted to permit only one ball in said trap to pass therethrough and come to rest in the tube 15 on the top of the piston. When the trigger is released the loading lever 137 will rise, thus permitting the levers 21 and 25 to resume the positions they occupied before the pulling of said trigger due to the pressure of the spring 30 forcing the piston 29 upwardly. It thus results that 105 the ball 35 resting on top of the piston is 110 thrown upwardly out of the tube 15, striking the under surface of the target plate 3 as at 36 and carroming therefrom onto the platform 16 from which it will eventually roll into the receiving tube 151 of the pistol 115 all as will be clear from Fig. 3. No other ball can enter the elevator tube 15 until the trigger of the pistol is again pulled, as from Fig. 2 it will be seen that the piston 29 120 seals the opening 31, or at least prevents the ball 37 from entering said tube. The short end of the lever 25 may always be actuated by the lever 21 due to the extended arcuate end 24 of the latter.

The elevator tube 15 is angularly disposed 130

as clearly indicated in the drawings to insure the ball 35 rolling therein and remaining in proper position to be expelled by the piston 29, instead of rolling back into the trap 9. Also, the inclination of said tube creates a better cooperation between the lever 25 and said piston 29 since the pin 28 connecting the same works in a slot 40 disposed longitudinally in the wall of the 10 elevator tube 15, and it is highly desirable to make the travel of the pin 28 in a line closely approximating an arc struck from the pivot 26 of the lever as a center. To permit the above mentioned cooperation, the 15 end of the lever 25 is slotted for travel of said pin 28. Still another advantage in inclining the tube 15, which is supported at its base by an extension 41 of the bracket 27, is to insure a ball expelled therefrom 20 being deflected from the underside of the plate 3 in a direction preventing its re-entering said tube.

This device is provided with means for scoring or registering the pockets through 25 which the balls drop. The actuating lever 82 described in the above mentioned patent forms a part of this device, and while it does not directly operate the counting or 30 registering mechanism yet one end 88 thereof extends out of the pistol 10 just as did the corresponding end of the same lever disclosed in said patent. This end 88 is adapted to coact with an arcuately formed plate 50 rigidly mounted on the end of a push rod 35 51 the other end of which is adapted to set the register to a zero reading. Stated in other words, when a coin is inserted in the pistol 10 and the coin slide described in said 40 patent is operated, the end 88 of the lever 82 is moved out of the pistol into contact with the curved plate 50. Continued movement against said curved plate causes the bar 51 to be moved to the right as seen in Figs. 2, 5 and 6 with the result that the 45 other end 52 of said rod comes in contact with a pin 53 mounted on a plate 54 freely pivoted as at 55 to a quadrant 56 having secured thereto a curved plate 57 on the exposed surface of which is printed or otherwise 50 formed designations indicating the score obtained by those balls which have passed through holes 6.

That is to say, beneath the plate 3 there depends a vertical bracket 58 on which the 55 quadrant 56 is mounted as by the pivot 55, a light spiral spring 59 being interposed between the fixed pivot 55 and the quadrant member 56 to cause said member to move clock-wise about its pivot as seen in Fig. 2. 60 The quadrant carries a pin 60 to which is secured one end of a helical spring 61 the other end of which is secured to a pin 62 mounted on the plate 54 to cause said plate to normally come to a rest position with 65 one of its sides against a stop-pin 63 also

mounted on said quadrant. The quadrant is further provided with a circular hub portion the edge of which is provided with teeth 64 adapted to be engaged by a double detent 65 pivoted as at 66 to the vertical bracket 70 58. Said detent has rigidly secured thereto an arm 70 extending in a substantially horizontal direction and normally resting on the upper side of a stop pin 71 mounted on the vertical plate 58. To the free end of this 75 arm 70 is secured a link 72 extending upwardly and attached at its upper end to a lever 73 pivoted as at 74 to a second vertical bracket 75 beyond which the lever extends as indicated at 76 to and through an opening 77 in the bottom of the trap 9 so that as a ball rolls over the bottom of said trap it will strike the end 76 of the lever 73 and tilt the same about its pivot. This action causes the link 72 to raise the end of the 80 arm 70 and rock the double detent 65 about its pivot 66. The teeth of the detent 65 are so spaced that when this rocking occurs, the quadrant 56 will be permitted under the 85 action of the spring 59 to rotate about its 90 pivot 55 a distance controlled by and equal to one of the teeth 64 associated with said quadrant.

The result of this action will be readily understood from the drawings but may be 95 stated as follows. Each time a ball passes through one of the openings 6 in the target plate 3, it will roll through the associated trough 7, enter the trap chamber 9, strike the end 76 of the lever 73, and cause the 100 quadrant 56 to turn about its pivot through a predetermined degree of arc. Said end 76 then resumes its raised normal position and the quadrant remains in the position to which it has just moved until a subsequent 105 ball rolls into the trap 9 and the same operations are repeated, whereupon the quadrant will move to a new position. The designations are spaced on the arcuate member 57 110 disposed at the periphery of the quadrant member, and a sight window 80 is provided in the target plate 3 directly over said member so that the designations are made visible to the operator of the device as they successively appear upon rotation of the quadrant. 115 Adjustability of the parts just described are made possible by securing the link 72 to the detent arm 70 by means of the screw 90 with nuts above and below an angular projection 91 of said arm. 120

After the predetermined number of balls have been fired from the pistol for the coin inserted therein, the pistol is automatically locked, as disclosed in said above mentioned patent, and the registering quadrant is left 125 in the last position to which it was moved. When the next coin is inserted in the pistol and the operating slide moved, the bar 51 will be moved to the right as seen in Fig. 6 and its end 52 will strike the pin 53 carried 130

by the plate 54 causing a rotation of the latter. The spring 61 associated with said plate 54 is made sufficiently strong to cause the quadrant member 56 to be rotated in a counter-clock-wise direction as seen in Fig. 2 and reset, or in other words, turned to its zero indicating position. Movement in said counter-clock wise direction is stopped, by a pin 92 mounted on the vertical bracket 58, at said zero indication. The resetting bar 51 is provided with a slot 94 adapted to receive in working cooperation therewith a pin 95 rigidly carried by the vertical bracket 58, and said bar is also provided with a second slot 96 to receive a pin 97 rigidly supported by the bracket 75, said pins and slots serving as means to guide the bar 51 and to control the longitudinal extent of its movement. A brace 100 may be provided to strengthen the arcuate member 50 carried by the rod 51, and a spring 101 disposed between said rod and the bracket 75 insures a return of said rod to position where it may be actuated by the end 88 of the pistol rod 82.

Summarizing the foregoing it will thus be seen that by this invention there is produced an amusement device including a pistol adapted to be unlocked by an inserted coin, to fire a determined number of balls for each coin inserted and become automatically locked thereafter, in combination with a target, means for returning balls to the pistol, means for registering the openings through which the fired balls passed, and means for resetting the registering means. Further it will be readily seen from the drawings that of all the balls fired from the pistol some may enter the openings 6 in the target 3 for establishing a score, while those which do not pass through said openings may roll from the target plate into a pocket formed by suitable side walls and the platform 16 from which said balls may pass into the pistol. Those balls which pass through the openings 6 will roll through the conduits 7 into the trap 9 common to all of said conduits and be elevated by the piston 29 into the pocket aforementioned and having the platform 16 having a bottom for ultimately reloading into the pistol. The elevating means comprising tube 15 and piston 20 constitute a separation between said pocket and the trap 9, and said piston is actuated by the firing means of the pistol. The registering means comprises a pivoted member under the tension of the spring 59, adapted to be released by the detent 65 which is controlled or operated by the releasing lever 73 having the end 76 extending within the trap 9 so that as the ball enters said trap it will pass over the end 76 and actuate the registering means. Lastly the means for resetting the registering means comprises the push rod

51 adapted to be actuated by the lever 82 associated with the pistol unlocking mechanism, said rod 51 adapted for reciprocable movement and further adapted to coact with one end of a freely pivoted member 54 held under the tension of the spring 61, said freely pivoted member being mounted co-actively with the registering member.

It is obvious that those skilled in the art may vary the details of construction as well as arrangement of parts without departing from the spirit of the invention, and therefore it is not desired to be limited to the above disclosure except as may be required by the claims.

What is claimed is:—

1. In a device of the character described the combination of a firing means for successively ejecting a predetermined number of balls, a target over which said balls may be rolled by said means, said target provided with a plurality of openings through which some of said balls may drop; conduits associated with said openings; a trap common to all of said conduits; means actuated by the firing means to recover balls conducted to said trap; and means to register the balls passing through said openings.

2. In a device of the character described the combination of a firing means for successively ejecting a predetermined number of balls, a target over which said balls may be rolled by said means, said target provided with a plurality of openings through which some of said balls may drop and a pocket into which other of said balls will enter; conduits associated with said openings; a trap common to all of said conduits; means actuated by the firing means to individually recover balls conducted to said trap and pass the same into said pocket; and means to register the balls passing through said openings.

3. In a device of the character described the combination of a firing means for successively ejecting balls, a target over which said balls may be rolled by said means, said target provided with a plurality of openings through which some of said balls may drop and a pocket into which other of said balls will enter; conduits associated with said openings; a trap common to all of said conduits; means for passing balls from said trap into said pocket; means for individually recovering balls from said pocket both of said last named means actuated by the firing means; and means to register the balls passing through said openings.

4. In a device of the character described the combination of a firing means, a target over which balls may be rolled by said means, said target provided with a plurality of openings through which some of said balls may drop and a pocket into which other of said balls will enter; conduits asso-

ciated with said openings; a trap common to all of said conduits; means constituting a portion of a wall of said trap to recover balls conducted to said trap and pass the same into said pocket; and means to register the balls passing through said openings.

5. In a device of the character described the combination of a firing means, a target over which balls may be rolled by said means, said target provided with a plurality of openings through which some of said balls may drop; conduits for said balls associated with said openings; a trap common to all of said conduits for receiving the balls therefrom; means comprising a spring tensioned elevator to recover balls conducted to said trap; and means to register the balls passing through said openings.

6. In a device of the character described the combination of a firing means, a target over which balls may be rolled by said means, said target provided with a plurality of openings through which some of said balls may drop; conduits associated with said openings; a trap common to all of said conduits; means comprising a spring tensioned reciprocating member actuated by said firing means to recover balls conducted to said trap; and means to register the balls passing through said openings.

7. In a device of the character described the combination of a target over which balls fired from a pistol may roll, said target provided with a plurality of openings through which some of said balls may drop; conduits associated with said openings; a trap common to all of said conduits; means including a plunger adapted to be reciprocated by the firing means to recover balls conducted to said trap and return them to said firing means; and means to register the balls passing through said openings.

8. In a device of the character described the combination of a firing means, a target over which balls may be rolled by said means, said target provided with a plurality of openings through which some of said balls may drop; conduits associated with said openings; a trap common to all of said conduits; means actuated by said firing means to singly recover balls conducted to said trap; and means coactively associated with said trap to register the balls passing through said openings.

9. In a device of the character described the combination of a firing means, a target over which balls may be rolled by said means, said target provided with a plurality of openings through which some of said balls may drop; conduits associated with said openings; a trap common to all of said conduits; means actuated by said firing means to recover balls conducted to said trap; and means including a detent controlled spring tensioned member for successively in-

dicating the balls passing through said openings.

10. In a device of the character described the combination of a target over which balls may be rolled; said target provided with a plurality of openings through which some of said balls may drop; conduits associated with said openings; a trap common to all of said conduits; means to recover balls conducted to said trap; and means including a detent controlled spring tensioned member operated by a release member extending into said trap, said means being for visibly indicating the balls passing through said openings.

11. In an amusement device including a pistol adapted to be unlocked by an inserted coin, to fire a predetermined number of balls for each coin inserted and become automatically locked thereafter, the combination of a target over which said balls may roll and drop through openings into conduits leading to a common trap; means for simultaneously recovering the balls from said trap; while firing other balls from said pistol; registering means for indicating the openings through which the balls passed; and means for resetting the registering means.

12. In an amusement device including a pistol adapted to be unlocked by an inserted coin, to fire a predetermined number of balls for each coin inserted, and become automatically locked thereafter, the combination of a target over which said balls may roll and drop through openings into conduits leading to a common trap; pistol controlled means for recovering the balls from said trap; registering means for indicating the openings through which the balls passed; and means controlled by the pistol unlocking mechanism for resetting the registering means.

13. In an amusement device including a pistol adapted to be unlocked by an inserted coin, to fire a predetermined number of balls for each coin inserted, and become automatically locked thereafter, the combination of a target over which said balls may roll and drop through openings into conduits leading to a common trap; pistol controlled means for recovering the balls from said trap; registering means for indicating the openings through which the balls passed; and reciprocating and rotatable means actuated by the pistol firing mechanism for resetting the registering means.

14. In an amusement device including a pistol adapted to be unlocked by an inserted coin, to fire a predetermined number of balls for each coin inserted, and become automatically locked thereafter, the combination of a target over which said balls may roll and drop through openings into conduits leading to a common trap; pis-

- tol controlled means for recovering the balls from said trap; registering means including a detent released and controlled pivoted member for indicating the openings through 5 which the balls passed; and means including a spring tensioned freely pivoted member and a reciprocable rod coacting with one end thereof for resetting the registering means.
- 10 15. In a device of the character described the combination of a target over which balls may be rolled, said target provided with a plurality of openings through which some of said balls may drop; conduits associated 15 with said openings; a trap common to all of said conduits; means to singly recover balls conducted to said trap; and means for successively indicating the balls passing through said openings, said means controlled from said trap.
16. In a device of the character described the combination of a target over which balls may be rolled, said target provided with a plurality of openings through which some 25 of said balls may drop; conduits associated with said openings; a trap common to all of said conduits; means to singly recover balls conducted to said trap; and means for successively indicating the balls passing 30 through said openings, said means including a spring tensioned rotatable member controlled by an escapement operated from said trap.
17. In a device of the character described 35 the combination of a target over which balls may be rolled, said target provided with a plurality of openings through which some of said balls may drop; conduits associated with said openings; a trap common to all 40 of said conduits; means to singly recover
- balls conducted to said trap; and means for successively indicating the balls passing through said openings, said means including a spring tensioned rotatable member controlled by an escapement operated by a lever 45 extending into said trap.
18. In a device of the character described the combination of a target over which balls may be rolled, said target provided with a plurality of openings through which some 50 of said balls may drop; conduits associated with said openings; a trap common to all of said conduits; means to singly recover balls conducted to said trap; and means for successively indicating the balls passing 55 through said openings; said means including a rotatable member under spring tension provided with an edge portion of circularly arranged teeth adapted to be engaged by a pawl controlled from said trap.
19. In a device of the character described the combination of a target over which balls may be rolled, said target provided with a plurality of openings through which some 60 of said balls may drop; conduits associated with said openings; a trap common to all of said conduits; means to singly recover balls conducted to said trap; and means for successively indicating the balls passing 65 through said openings, said means including a rotatable member under spring tension provided with an edge portion of circularly arranged teeth adapted to be engaged 70 by a pawl controlled by a lever extending into said trap and actuated by each ball 75 passing therethrough.

In testimony whereof we affix our signature.
